UNITED STATES PATENT OFFICE.

JULIUS PORTESI, OF LOS ANGELES, CALIFORNIA.

GATE-LATCH.

1,260,444.

Specification of Letters Patent. Patented Mar. 26, 1918.

Application filed June 15, 1917. Serial No. 174,978.

To all whom it may concern:

Be it known that I, JULIUS PORTESI, a citizen of the United States, residing at Los Angeles, in the county of Los Angeles and State of California, have invented certain new and useful Improvements in Gate-Latches; and I do declare the following to be a full, clear, and exact description of the invention, such as will enable others skilled in the art to which it appertains to make and use the same.

My invention relates to improvements in latches and more particularly to gate latches and one object of the invention is to provide an improved latch of this character in which positive means are provided for actuating the keeper of the latch.

Another object of the invention is to provide in a latch of this character improved mechanism whereby a positive thrust will be imparted to certain parts thereof in order to open the gate when the latch is raised.

A further object of the invention is to provide an improved latch in which all parts are readily accessible and which may be readily operated, and which is simple, cheap to manufacture and readily applied.

With these general objects in view and with others that will appear from the description my invention resides in the novel construction, combination and arrangement of parts to be more fully hereinafter described and claimed when taken in connection with the accompanying drawings which form a part of this application and in which:

Figure 1 is a rear elevation of a gate showing my latch as applied;

Fig. 2 is a front elevation;

Fig. 3 is a side elevation of a portion of the gate post illustrating more in detail the mechanism of the latch;

Fig. 4 is a face view of the latch member;

Fig. 5 is a top plan view of Fig. 3;

Fig. 6 is a longitudinal section on the line 45 6—6 of Fig. 5;

Fig. 7 is a section taken on the line 7—7 of Fig. 3;

Fig. 8 is a horizontal sectional view taken on the line 8—8 of Fig. 6; and,

50 Fig. 9 is a detail view of the keeper spring. In the accompanying drawings I have illustrated my improved latch as applied to

a gate of the ordinary type comprising a horizontal swinging gate G and a stationary latch carrying post P. In detail the invention comprises a metal tongue 1 fastened to one side of the gate and having a laterally offset enlarged head 2 projecting beyond the end thereof and adapted to swing below a stud 3 projecting laterally from the post P and secured at one end to a face plate 4 suitably attached to the post so as to dispose the stud above the tongue 2. Vertically disposed on the post and suitably attached thereto at its lower end is a leaf spring 5 having its upper end disposed in the path of travel of the head 2 of the gate and tongue so that when the latch mechanism to be described, is raised the spring 5 will force the head 2 away from the post and cause the gate to swing open.

Attached to the stud 3 is a keeper for the gate tongue, comprising a substantially U-shaped bar 6 straddling the top of the stud 3 at the bend of the U and having the free ends of its arms 7 pivotally connected to the outer end of the stud as at 8. The intermediate portions of the arms 7 are inclined downwardly below the stud 3 from the integrally connected ends to a point disposed in laterally spaced relation from the post P, where they are bent upwardly in a vertical plane substantially parallel with the post to form the arms 7 which will provide a suitable keeper having an outer inclined face 80 and an inner vertically disposed face spaced a sufficient distance from the gate post to retain the head 2 of the tongue when the gate is closed.

The straddling support of the bend of the U of the keeper bar limits the downward movement of the keeper and will dispose the lower end thereof directly in the path of travel of the head 2 of the gate tongue so that when the gate is swung closed the tongue will ride on the inclined outer face of the bar 7 and lift the keeper, permitting the same to drop behind the tongue when it has traveled a sufficient distance toward the post. The spring 5 will then act to hold the tongue securely against the vertically disposed flat face of the keeper and in order to provide a positive means for insuring direct action of the keeper and preventing acci-

dental dislodgment thereof, I provide a spring tongue or leaf spring 8 secured at one end to a laterally projecting lug 9 carried by a shoulder 10 extending upwardly 5 from the outer end of the stud 3. The free end of the spring 8 bears against one of the arms 7 and will tend to normally hold the keeper in lowered operative position. The arms 7' of the keeper bar are merged above 10 the bend of the U and extended upwardly to provide a handle 11 suitably spaced from one side of the gate post and above the stud so that the keeper may be readily lifted by inserting the finger beneath the handle and 15 lifting the keeper against the tension of the spring 8.

Secured to the opposite face of the gate post and in alinement with the face plate 4 is a similar face plate 12. The face plates 20 and post are slotted in alinement to provide for the reception therethrough of an operating lever 13 pivotally mounted within the post on a pivot stud 14 extending transversely therethrough and carrying on the 25 end adjacent the plate 12 a handle 15. The opposite end of the lever is pivotally connected as at 16 to the handle 11 of the keeper so that when the handle 15 is depressed from the opposite side of the post the keeper will 30 be raised as if the handle 11 were manipulated, thereby providing a means whereby the keeper may be operated from either side of the post. A hand grip 16 is suitably secured on the gate post of the handle 15 of 35 the lever 13 so that a better leverage may be obtained when operating the latch.

In the operation of my improved latch, supposing the gate to be closed, the component parts will be in the position as illustrated in Fig. 3 and when either the handle 40 11 is raised or the handle 15 depressed the keeper bar will be raised against the tension of the spring 8 permitting the head 2 of the tongue 1 on the gate to be forced outwardly 45 under action of the spring 5 thereby automatically opening the gate and when pressure is relieved from the latch levers the spring 8 will automatically return the keeper to operative position, its downward movement being limited by the U bend in the 50 keeper bar straddling the stud 3. When the gate is swung closed the head 2 of the gate tongue will ride in on the inclined outer face of the keeper bar, lifting the same against 55 the tension of the spring 8 until it has passed the end of the inclined arm 7, whereupon the keeper will drop into lowered position and the tongue will be retained between the flat face formed by the arms 7' of the keeper and 60 the gate post and against the tension of the spring 5.

While I have described and illustrated in the accompanying drawings certain specific details and materials entering into the con-

struction and operation of my improved 65 latch, I desire to be understood that I do not intend to so limit myself to this structure as brought out, but that any changes may be made in the details thereof as will fall within the scope of the invention as claimed. 70

I claim:

1. A gate latch as described, comprising in combination, a gate, a post, a stud projecting laterally from said post, a bar pivotally connected at one end to the outer end of said stud, the other end of the bar being formed into a handle and adapted to be supported on said stud, the intermediate portion of said bar extending below said stud and bent to form a keeper, a spring between 80 said stud and bar to normally hold the keeper below said stud, a tongue on the gate to swing below said stud and be retained behind said keeper and a hand lever extending from the opposite side of said post and connected to the keeper handle. 85

2. A gate latch as described, comprising in combination, a gate, a post, a stud projecting laterally from said post, a substantially U-shaped arm straddling said stud, the ends 90 of the arms of said U being pivotally connected to the outer end of the stud with the bend of said U supported by said stud, the arms of said U being inclined downwardly from the pivotally connected ends and bent 95 substantially vertically upward in lateral spaced relation upon the post, to form a keeper below the stud, a lug projecting laterally from said stud, a leaf spring secured at one end to said lug and bearing 100 against an arm of said bar, a tongue on the gate to engage the inclined arms and raise said keeper when closing and to be retained between said post and vertical face of the keeper when closed, and handle mechanism 105 on the opposite sides of the post in connection with the keeper.

3. A gate latch as described comprising in combination, a gate, a gate post, a stud projecting laterally from said post, a substantially U-shaped keeper bar straddling said stud with the bend thereof supported on the stud to limit downward movement of the keeper, the arms of said bar being extended vertically below said stud and in 115 lateral spaced relation from said post and bent at an incline upwardly to the outer end of the stud, pivotal connection between the ends of said arms and outer end of the stud, a leaf spring secured at one end to the stud 120 and bearing against the arms of said bar to hold said keeper operative, a handle extending upwardly from said keeper to one side of the post, a handle extending through said post to the opposite side, pivotally mounted 125 therein and connected to said first-named handle, and a tongue on said gate to be retained by the keeper.

4. A gate latch as described comprising a post having a stud projecting laterally therefrom, a bar having one end pivotally connected to the outer end of said stud, the other end of the bar being formed into a handle the intermediate portion of said bar extending below said stud and bent to form a keeper, a spring disposed between said keeper to normally hold the keeper below the 10 stud, a tongue on the gate to swing below said stud and be retained behind said keeper, an operating bar pivotally connected to the keeper and extending through an aperture in said gate post, a stud disposed crosswise

in said aperture and extending through a slot in said operating bar and a handle on the other hand of the operating bar whereby when said handle is depressed said bar will slide on last mentioned stud and raise said keeper.

In testimony whereof I have hereunto set my hand in the presence of two subscribing witnesses.
